FURNACE

Original Filed Feb. 4, 1922 2 Sheets-Sheet 2

UNITED STATES PATENT OFFICE.

AUBREY J. GRINDLE, OF CHICAGO, ILLINOIS, ASSIGNOR TO GRINDLE FUEL EQUIPMENT COMPANY, OF HARVEY, ILLINOIS, A CORPORATION OF ILLINOIS.

FURNACE.

Application filed February 4, 1922, Serial No. 534,233. Renewed December 12, 1923.

To all whom it may concern:

Be it known that I, AUBREY J. GRINDLE, a citizen of the United States, residing at Chicago, in the county of Cook and State 5 of Illinois, have invented a certain new and useful Improvement in Furnaces, of which the following is a specification.

This invention relates to furnaces. It is specially applicable to annealing furnaces 10 and for the heating of all sorts of products requiring heat in the process of manufacture.

In furnaces of the general class set forth, it is necessary to bring the flames which produce the heat or the products of combustion thereof into the furnace in contact with the articles to be heated, this being particularly true where powdered coal is used as a fuel.

20 The object of this invention is to construct a furnace with flues for carrying the products of combustion from the furnace to the stack or other discharge device so arranged that the major part of the dust or 25 ash which is necessarily found in the hot gas or other product of combustion, is deposited in such a position that it can be readily withdrawn without its passing up the stack and out into the open air. An 30 other principal object of the invention is to construct the flues so that they cannot become clogged by the passing ash or dust, this primarily by providing ready means of 35 withdrawing the deposited ash or other waste product.

The invention consists in a device capable of attaining the foregoing objects, which can be comparatively easily and cheaply constructed, which is very simple and efficient 40 in operation and is not readily liable to get out of order. More particularly, the invention consists in numerous features and details of construction which will be hereafter more fully set forth in the specification and 45 claims.

Referring to the drawings, in which like numerals designate the same parts throughout the several views—

Figure 1 is a sectional plan view of a 50 structure illustrating this invention in its preferred form;

Figure 2 is a central vertical sectional detail view, on the line 2—2 of Figure 1;

Figure 3 is a sectional end view, taken on the irregular line 3—3—3 of Figure 1; 55

Figure 4 is an exterior end view taken at the right hand end of Figure 2;

Figure 5 is a sectional detail view of a damper take at approximately the line 5—5 of Figure 1; 60

Figure 6 is another detail view of the same damper taken on approximately the line 6—6 of Figure 1; and

Figure 7 is an enlarged end detail view of the lever operating mechanism for the dampers shown in Figures 5 and 6. 65

The device of this invention is shown applied to a furnace having a main floor 10 on which the articles to be heated are adapted to be placed in any suitable manner. About this floor are two parallel side walls 12, a rear wall 14 carrying a conventional form of stack 16, a set of removable front doors 18 and a curved roof 20, all of conventional form, except as to details 70 hereafter described. In the operation of the furnace thus far described, the doors 18 are wholly removed by conventional forms of truck mechanism well known in the art; the material to be heated is placed on the floor 10, the doors 18 are replaced in position and sealed up in conventional manner, whereupon the furnace is ready 75 for the application of heat.

In applying this invention to this conventional form of furnace just described, the walls 12 are provided with horizontally placed flutes or passages 22, communicating at the rear of the furnace with connecting transverse passages 24, leading into the stack 16. These passages 22 and 24 are of sufficient height above the top of the floors 10 that the bottoms of the passageways can be constructed in saw tooth cross section 26 or 28 of sufficient height so that gas 80 intake passages 30 or 32 can be constructed below the bottom of the saw tooth formation and adjacent to the upper surface of the floor 10, and there is enough clearance 85 space between the upper ridges 34 or 36 of the different sets of saw teeth and the interior roof surfaces 38 of the flues 22 and 24 so that a clear passage is furnished for heated gases along the flues 22 into flues 24 and thence out of the stack 16. 90

95 The angularity of the saw tooth cross sec-

tion bottoms of the flues 22 and 24 should be such that as hot gas passes through the flues to the stack and dust is deposited from the gas on the inclined faces of the saw tooth section bottoms of the flues 22 and 24, substantially all of the dust so deposited will slide down the inclined surfaces and drop into the openings 30 or 32, as the case may be.

10 Certain of the openings 30 located at the front of the furnace, in the particular case here illustrated the first two, in each side wall 12, are equipped with dampers 40 adapted to be opened and closed by any 15 suitable means, operatable from outside the furnace. In the particular case here illustrated, this is accomplished by mounting these dampers on shaft 42, each selectively controllable by a handle 44 located on the 20 front of the furnace and rockable through ninety degrees from engagement with one stop 46 to engagement with another stop 48. In the illustration herein, the means for locking this handle 42, and consequently 25 the dampers, in selected positions, is a pin 50 carried by a chain 52, the pin being selectively insertable in holes 54 or 56, as the case may be, provided adjacent to the stops 46 and 48.

30 In similar manner, a certain number, in the particular case here illustrated, two of the openings 30 in the rear parts of the side walls 12 are equipped with dampers 59 mounted on a control shaft 60 conventionally 35 operatable from the rear of the furnace by a lever 62 corresponding to hand lever 44.

The roof 20 is by preference placed, as shown in Figure 1, with its rear end 64 substantially higher than its front end 66, so 40 that the inner surface 68 is inclined downwardly from the rear of the furnace towards the front. The rear wall 14 is recessed at 70, immediately adjacent to the upper end 64 of the roof, to permit the insertion of a plurality, in the particular case here illustrated, two, fuel nozzles 72 for the introduction of any sort of fuel, preferably but not necessarily powdered coal, the same being supplied to these nozzles by suitable supply 45 pipes, not shown, extending to the left beyond Figures 1 and 2.

In the operation of the furnace thus constructed, and loaded with material to be heated, as heretofore described, the nozzles 55 72 are lighted, with the result that the products of combustion from the fuel material entering the furnace through said nozzles pass in well known manner along the interior surface 68 of the roof 20 both 60 toward the front end of the furnace and more or less downwardly toward the floor until the entire furnace chamber is filled with hot gases, which must escape, and this escape is provided by the perforations 30 and 65 32 in the bottoms of the respective flues

22 and 24. When the gas does so pass into the openings 30 and 32, it ascends over the sides of the saw tooth bottom members 26 and 28 in these flues, depositing more or less ash or other solid material thereon, and finally in the obvious manner, passes to and out of the stack 16. Because of this depositing of ash on the saw tooth section bottoms of the flues, the ash obviously does not pass out of the stack to the annoyance of 75 third parties adjacent to the furnace. Owing to the inclination of the ridges in the saw tooth bottoms of these flues 22 and 24, the ash, as formed, slips in large measure down the inclined surfaces of the bottoms 80 of the flues into the bottoms of the openings 30 and 32, where it rests on the floor in little piles until opportunity occurs, due to the non-use of the furnace, frequently after several days, for the removal of the 85 ash. This is accomplished in the particular furnace here illustrated by entering the furnace when cold and shoveling out the little piles of ash from the bottoms of the openings 30 and 32.

90 The furnace may be regulated to accommodate material to be worked upon in different quantities or differently positioned in the furnace by regulating the dampers 40 and 59 in obvious manner to cause the hot 95 gas furnished by the nozzle 72 to distribute itself through various combinations of the openings 30 as the work in hand may require. In other words, by properly partially or wholly opening various combinations of 100 the dampers 40 and 59, uniform heat throughout the furnace may be established and maintained.

105 This construction of flue with saw tooth section bottom and clean-out openings at the floor level of the furnace is, so far as I am aware, wholly new and applicable to a great many types of furnace other than the particular one shown in the drawings. Attention is called to the fact that the flues 22 and 24 do not have to be provided with any 110 openings for removal of ash or dust except the normal gas intake openings 30 and 32 leading to them, which have to be provided any way and through which the waste ash or dust is ultimately removed.

115 While it does not enter into the invention it may be stated that the stack 16 is provided with a conventional shut-off damper 74 for closure when the heat is shut off, to retain the previously generated heat within the furnace.

120 The bottom of the stack is preferably, but not necessarily provided with a conventional form of clean-out door 76.

125 What I claim is:

1. In mechanism of the class described, a flue for the passage of gas to a stack or the like provided with a bottom of saw tooth cross section over which gas in the flue 130

passes, there being, in the bottoms of the saw tooth notches in the flue bottom, openings through which solid particles deposited by passing gas may slide by gravity out of the flue, for the purposes set forth.

2. In mechanism of the class described, a furnace having side walls, a floor, and means for supplying hot gas inside the furnace, a flue in a side wall leading to a gas exit 10 passage, said flue being provided with a bottom of saw tooth cross section over which gas in the flue passes, there being, in the bottoms of the saw tooth notches in the flue bottom, openings through which solid particles deposited by passing gas may slide out of the flue, said bottom openings in the flue being adjacent to the furnace floor so that solid particles deposited from the flue fall onto the furnace 15 floor, and dampers for selectively closing certain of said bottom openings, for the purposes set forth.

3. In mechanism of the class described, a furnace having side walls, a floor, and means for supplying hot gas inside the furnace, a flue extending substantially the length of a 20 side wall leading to a gas exit passage, said flue being provided with a bottom of saw tooth cross section over which gas in the flue passes, there being, in the bottoms of the saw tooth notches in the flue bottom, open-

ings through which solid particles deposited by passing gas may slide out of the flue, said bottom openings in the flue being adjacent to the furnace floor so that solid particles deposited from the flue fall onto the furnace 25 floor, and dampers for selectively closing certain of said bottom openings, for the purposes set forth.

4. In mechanism of the class described, a furnace having side walls, a floor, and means for supplying hot gas inside the furnace, a flue 30 extending substantially the length of a side wall leading to a gas exit passage, said flue being provided with a bottom of saw tooth cross section over which gas in the flue passes, there being, in the bottoms 35 of the saw tooth notches in the flue bottom, openings through which solid particles deposited by passing gas may slide out of the flue, said bottom openings in the flue being adjacent to the furnace floor so that solid 40 particles deposited from the flue fall onto the furnace floor, dampers for selectively closing certain of said bottom openings, and means outside the furnace for operating 45 said dampers.

In witness whereof, I have hereunto subscribed my name.

AUBREY J. GRINDLE.
